ACOUSTICAL CABINET FOR LOUDSPEAKERS
Richard M. Smith, 318 6th St., Greenport, N.Y.
Filed June 28, 1963, Ser. No. 291,416
4 Claims. (Cl. 181—31)

This invention relates to sound reproducing apparatus and more particularly to an acoustical cabinet which increases or amplifies the sound radiating output of a loudspeaker. The principles underlying operation of the present invention are similar to those disclosed in my prior copending application U.S. Serial No. 137,655, filed September 12, 1961, now U.S. Patent 3,115,208.

It is therefore a primary object of the present invention to provide an improved loudspeaker cabinet particularly suitable for mounting of small and inexpensive loudspeakers of the radiating cone type so as to produce a speaker system of unexpectedly high efficiency and acceptably faithful reproduction characteristics. The output range from the acoustical cabinet of the present invention is therefore comparable in performance to that of the more expensive speaker systems and wherein the acoustical cabinet occupies a significantly larger volume and/or floor space.

The principle underlying the demonstrated successful results obtained with the acoustical cabinet of the present invention, may be attributable to the vibration-free mounting of the loudspeaker on a baffle member which separates the enclosure into a front and rear chamber similar to the arrangement disclosed in the aforementioned prior copending application. Thus, optimum results have been obtained through experimentation with such an equal volume relationship, this being possibly attributable to the relative loading of the radiating cone or cones of the loudspeakers both forwardly and rearwardly thereof because of the recessing of the speaker mounting member so as to produce a cushioning effect on the speaker diaphragm, eliminating mingling of sound and approaching the theoretically perfect speaker baffling arrangement. The acoustical cabinet is also provided with a vented back panel providing compressional relief vents for the rear chamber in order to avoid stiffening of the speaker diaphragm or cone. In order to further improve and enhance operation of the speaker system, the acoustical cabinet device of the present invention further includes passages surrounding the front and rear chambers and separated therefrom so as to establish passages between the open front of the acoustical cabinet and the rear chamber adjacent the back panel. It has therefore been found, that the additional venting for the rear chamber and passageways formed about the chambers conducting sound energy toward the open front, reinforces the output from the forwardly radiating speaker or speakers mounted on the baffle member.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the acoustical cabinet device of the present invention as seen from the front.

FIGURE 2 is a perspective view of the acoustical cabinet as seen from the rear.

FIGURE 3 is a front elevational view of the speaker cabinet with the front grille removed.

FIGURE 4 is a rear elevational view of the speaker cabinet with the back panel removed.

FIGURE 5 is a top sectional view through the speaker cabinet taken substantially through a plane indicated by section line 5—5 in FIGURE 1.

2

FIGURE 6 is a transverse sectional view through the speaker cabinet taken through a plane indicated by section line 6—6 in FIGURE 1.

Referring now to the drawings in detail, one exemplary form of speaker cabinet is illustrated in FIGURES 1 and 2 generally referred to by reference numeral 10. The cabinet encloses an outer chamber 11 defined by interconnected outer walls including parallel spaced top wall 12 and bottom wall 14 interconnected by side walls 16 and 18. All of the interconnected walls are rectangular in shape defining a completely open rectangular front which may be covered by a grille 20 while a back panel 22 is secured in place in the rear opening of the cabinet enclosure. The cabinet may be mounted in any suitable manner and at any suitable location as for example by the legs 24 spacing the enclosure above a supporting floor.

As more clearly seen in FIGURES 3—6, the outer walls of the cabinet are rigidly interconnected with the top and bottom walls 12 and 14 being disposed in edge-abutting relation to the side walls 16 and 18. These walls are formed from a vibration-dampening material such as a material marketed under the name of "Homasote," cut from panels preferably one inch in thickness. A decorative veneer 26 may be cemented in place on the externally exposed surfaces of the outer walls in a manner well known. The back panel 22 is also formed of the same vibration-dampening material and is secured in place by a pair of mounting strips 28 secured to the rear edges of the top and bottom walls 12 and 14. The back panel is dimensioned so that when it is mounted within the back opening of the cabinet enclosure, it will be equally spaced from the top and bottom walls and side walls providing a continuous peripheral vent opening 30. The back panel may therefore be imperforate except for the mounting therein of any components associated with the speaker system such as the volume control element 32 and the terminal connection element 34 as seen in FIGURES 2 and 5.

Also associated with the speaker system, will be one or more loudspeakers including a main speaker 36 of the radiating cone type having a driver portion 38 through which electrical energy is converted into mechanical energy vibrating the cone portion 40 for radiating sound energy both forwardly and rearwardly therefrom. The main loudspeaker unit 36 is therefore mounted together with other speaker components 42 and 44 if utilized on a baffle member 46 provided with openings receiving the sound radiating cone or horn if this type of auxiliary speaker unit is utilized. The baffle member 46 is otherwise imperforate and secured in place by side passage members 48 and 50 and top and bottom passage members 52 and 54. The side passage members 48 and 50 are disposed in equal spaced parallel relation to the side walls 16 and 18 so as to define side passages 56 and 58 while the members 52 and 54 are respectively disposed parallel to the top and bottom walls 12 and 14 so as to define top and bottom passages 60 and 62. The passage members are also made of the same sound-dampening material mentioned in connection with the outer wall members and enclose an inner chamber 13 including a front chamber portion 64 and a rear chamber portion 66 on opposite sides of the baffle member 46. The baffle member is secured within the passage members so as to separate the front and rear chamber portions into substantially equal volumes. The front chamber portion 64 therefore extends from the baffle member forwardly to the open front end of the cabinet so that forwardly radiating sound energy from the speaker cones will emanate therefrom. The rear chamber portion 66 on the other hand, extends from the baffle member rearwardly terminating in spaced adjacency to the back panel 22. The rear chamber portion 66 is therefore in fluid communication with the

open front end by means of the rear space 55 and passages 56, 58, 60 and 62 which completely surround the front and rear chamber portions. Sound radiated by the speaker diaphragms in a rearward direction will cause compression and rarefaction of the air within the outer chamber which will be vented by the vent opening 30 while some of the sound energy itself may be reflected by the back panel and passed through the surrounding passages out through the open front for reinforcing the forwardly radiating sound energy.

The dimensions of the various parts forming the speaker enclosure are selected in accordance with the foregoing constructional principles amongst which there is the equal volume requirement for the front and rear chamber portions 64 and 66, the formation of a vent opening 30 in the rear opening of the enclosure and the size of the main speaker 36.

From the foregoing description, the construction, operation and utility of the acoustical cabinet device of the present invention will be apparent. The dimensions of the cabinet are critical only in connection with the equal volumes of the front and rear chamber portions, relative to dimensions of the surrounding passages and rear vent opening. Also, the selection of a sound-dampening material for the enclosure walls and chamber walls as well as for the speaker mounting baffle member, are important. Also important is the open front arrangement so that sound waves radiated forwardly from the speaker may diverge without obstruction while the rearwardly radiated sound energy is partially reflected while the vent opening 30 provides compressional relief so as to avoid cone stiffening. Also, the relative loading of the speaker cone both forwardly and rearwardly produces the aforementioned cushioning effect by virtue of which the extended volume range of the speaker system is attained utilizing less costly and smaller speaker units as well as a dimensionally less extensive speaker cabinet.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An acoustical cabinet for a loudspeaker having a sound radiating element comprising, interconnected outer walls forming an outer chamber extending between a completely open front end and a rear end, inside walls connected to said outer walls forming an inner chamber portion cross-sectionally larger throughout than the sound radiating element and extending from said front end a distance short of the rear end, said inner chamber portion being spaced from the outer walls to form surrounding passageways extending rearwardly from said front end, a baffle member connected to the inside walls completely dividing said inner chamber portion into substantially

equal parts, said baffle member having an opening therein mounting the sound radiating element of the loudspeaker, a rigid back panel substantially closing the outer chamber at the rear end, and means securing said back panel in spaced relation to the outer walls to form a peripheral vent opening for the outer chamber aligned with said passageways.

2. The combination of claim 1 wherein said walls are made from flat panels of vibration-dampening material to form the inner and outer chamber rectangular in cross-sectional area.

3. An acoustical cabinet in combination with a loudspeaker having a radiating cone comprising, an enclosure having walls defining an elongated chamber cross-sectionally larger than the radiating cone, a rigid back panel, an imperforate baffle member supporting the loudspeaker thereon, means secured to said walls for mounting the baffle member intermediate opposite ends of the chamber and forming front and rear chamber portions on opposite sides of the baffle member to load the radiating cone both forwardly and rearwardly within the enclosure, said walls of the enclosure being formed of vibration-dampening material enclosing said front and rear chamber portions, one of said opposite ends of the chamber being completely open and acoustically unobstructed, means securing said rigid back panel to the enclosure at the other of the opposite ends in spaced relation to the walls to form compressional relief vents rearwardly spaced from the rear chamber portion, and sound passage means externally surrounding the baffle member and isolated from said front and rear chamber portions within the enclosure establishing communication between the open end and the rear chamber portion adjacent the back panel, said rear chamber portion terminating in spaced adjacency to said relief vents.

4. The combination of claim 3 wherein said passage means is formed by chamber forming members disposed in spaced parallel relation to the walls of the enclosure and made of said vibration-dampening material.
